UNITED STATES PATENT OFFICE.

EUGÈNE HENRI TARTRAIS, OF MAISONS-LAFFITTE, FRANCE.

PUMP FOR FEEDING LIQUID-FUEL ENGINES AND LIKE APPLICATIONS.

1,315,648.

Specification of Letters Patent. Patented Sept. 9, 1919.

Application filed November 21, 1918. Serial No. 263,580.

To all whom it may concern:

- Be it known that I, EUGÈNE HENRI TARTRAIS, citizen of the Republic of France, residing at 3 Rue de Mexico, Maisons-Laffitte, 5 Seine and Oise, in the Republic of France, have invented new and useful Improvements in Pumps for Feeding Liquid-Fuel Engines and like Applications, of which the following is a specification.
- 10 This invention has for its object the provision of a pump by means of which small quantities of liquid fuel accurately measured may be injected, under high pressure and at a precise moment of the cycle, into 15 the cylinder of a high speed engine.
- My experiments enabled me to discover that, besides the influence of leakage, which it is always possible to reduce to zero owing 20 to a good construction, the main obstacle results from the presence of air or gases in the liquid to be injected. Said gases, remaining in the pump, or in the delivery pipe, have a double effect: in the pump, they lessen its delivery, in the piping, they form 25 an elastic buffer so that the liquid is introduced into the engine, not at the moment the pump is giving its forcing stroke, but at the moment at which the pressure in the cylinder is minimum.
- 30 My experiments have also shown that said gases come from the mass of the liquid itself, as, for the same pump, the result is wholly different according as said pump is acting upon petrol or recently boiled water, leakage being absolutely reduced to zero in the 35 two cases. Said gases seem to be given off under the action of the slight depression taking place at the moment of suction and afterward not to liquefy with a sufficient 40 speed.

In my experiments, I was operating with an ordinary pump with a piston and automatic suction valve, and I replaced said valve by a non-automatic valve, preserving 45 the same manner of opening, that is to say from outside to inside in respect of the pump barrel. The result, still bad, seemed to show that the valve was not large enough. However, enlargement of the valve gave a worse 50 result with respect to the presence of the gases. The reason is that the head of the valve itself operates as a piston. At the moment it closes, it tends to create a vacuum in the barrel of the pump, a vacuum that 55 cannot be filled with sufficient speed owing

to the narrow section of passage under the seat.

The above considerations led to the execution of the pump object of the invention and the excellent results obtained with this 60 apparatus confirmed the correctness of the above explanations.

Referring to the annexed drawing, showing by way of example a form of construction of the pump in accordance with the invention:

Figure 1 is a vertical section of the pump taken through the axis of the operating shaft;

Fig. 2 is a diagram relating to the respective lifting movements of the piston of the pump and of the inlet valve;

Fig. 3 shows in vertical section a modified construction in which the delivery valve is located in the inlet valve;

Fig. 4 shows in vertical section a particular connection of the inlet valve to the delivery piping, in the case where the modification of Fig. 3 is used.

Referring to Fig. 1, 1 indicates the cam shaft,—2 the cam operating the pump piston,—3 the cam operating the inlet valve,—4 the frame of the apparatus,—5 the pump piston,—6 a stuffing box for said piston,—7 the return spring of said piston,—8 the pump cylinder or barrel,—9 the inlet valve,—10 the guide for said valve,—11 the spring for the said inlet valve,—12 the operating rod for said inlet valve,—13 the return spring for said rod,—14 the operating arm for said inlet valve, said operating arm being rigidly connected to the rod 12,—15 the constant level reservoir for the liquid fuel,—16 the passage connecting said reservoir to the chamber 17,—17 the liquid chamber provided around the suction valve and closed, at its lower part, by said valve,—18 the lower part of the constant level reservoir through which comes the liquid which, as usual, passes through a filter before entering the body 15 of said reservoir,—19, 20 the liquid level in the reservoir 15 and chamber 17,—21 air holes bored at the upper part of chamber 17,—and 22 the automatic forcing valve.

In Fig. 1, the piston 5 is shown at the higher point of its stroke. It will be noted that the undesirable space is reduced to about nothing (it could be made wholly equal to zero as disclosed thereafter) and 110

that the inlet or suction valve has a relatively large section. It will be seen that said valve opens from inside to outside. The spring 11 must have sufficient strength 5 to balance the internal pressure at the moment of injection.

It is useful to call attention to the precautions taken in order to prevent formation of the gases and in order to prevent their 10 settling notwithstanding their formation.

At the moment the valve 9 lifts, there is produced, as explained, a relative vacuum in the cylinder capable of freeing some gases. But the quantity of liquid upon 15 which said vacuum is acting being very slight, it can only give a slight quantity of gases. Besides, the counter part will be seen later. When the piston commences its suction, the valve is sufficiently open to 20 allow the suction to take place as easily as possible. In this operation, the chamber 17 plays a double function. Owing to the air holes 21, it enables the pump to take its full stroke, eliminating the effects of inertia in 25 the piping and the resulting cavitations. Moreover, should atmospheric air have been accidentally introduced through the passage 16, it will escape through holes 21. When the piston reaches the end of its descending 30 stroke, the valve commences to close. Should gas bubbles exist, they tend to rise to the upper part of the cylinder. The valve, when closing, (this is the counter part referred to) tends to produce a slight compression in the 35 mixture. A slight quantity is necessarily forced out together with any gas bubbles which may be present.

Fig. 2 shows diagrammatically the respective lifting movements of the piston and 40 valve. 24, 28 is the curve relating to the piston; 29, 34 is the valve curve; 25, 26 lowering of the piston, that is to say suction; 26, 27 stopping at the lower dead point; 27, 28 lifting of the piston, that is to say delivery 45 of very short duration (injection period); 30, 31 opening of the valve; 32, 33 closing. It will be seen that the valve opens before the piston commences its descending stroke and closes after said stroke is completed.

50 It is desirable to make all the delivery piping together with the valve chamber of very narrow section and of such forms that the flowing speed of the liquid will be great enough to positively expel the slightest gas bubble which could, in spite of all, exist. It is also necessary that the piping be short in order to have a slight volume of liquid between the pump and the engine to prevent the troublesome effects due to the compressibility of the liquid or to the resiliency of 55 the walls containing same.

In Fig. 1, a key will be noticed at 23. Said key is wedge shaped at right angles to the plane of the figure and may be more or less 60 driven in order to limit the return stroke of

the piston and the suction in view of the necessities of regulation of the engine. The process is a known one. Others answering the same purpose may be used. Said detail forms no part of the invention.

70 It was stated above that the volume of the undesirable space could be still further reduced. In effect, in Fig. 1, it will be seen that it is reduced to a very short passage 35 leading to the delivery valve 22. In order 75 to dispense with said space, the delivery valve can be placed in the inlet valve, concentrically with the latter, as shown in Fig. 3. The suction valve then forms a part of the delivery passage. It is connected with 80 the piping either through a flexible member *ad hoc* (pipe 36) or else, Fig. 4, its upper end may enter a stuffing box 37 and the delivery piping will be then connected to a joint such as 38.

85 Obviously, the above described pump may be used with equally good results to inject water or any other liquid either into engines or into air or other gas compressors.

Having now described my invention, what 90 I claim as new and desire to secure by Letters Patent is:

1. A pump for feeding engines with liquid fuel comprising, in combination: a cam shaft, a pump barrel or cylinder, a 95 pump piston subjected to the action of one of the cams, a return spring maintaining the contact between the piston and the cam,—an inlet or suction valve located in line with the piston axis and forming the bottom or 100 end of the pump body or barrel,—means for mechanically operating said valve and allowing it to open from inside to outside,—a liquid chamber around the suction valve and outside of the pump barrel and an 105 automatic delivery valve opening into the pump barrel below the suction valve, substantially as described and for the purpose specified.

2. A pump for feeding engines with 110 liquid fuel comprising, in combination: a cam shaft, a pump barrel or cylinder, a pump piston subjected to the action of one of the cams, a return spring maintaining the contact between the piston and the cam,—an inlet or suction valve located in 115 line with the piston axis and forming the bottom or end of the pump body or barrel,—means for mechanically operating said valve and allowing it to open from inside to outside,—a liquid chamber around the suction valve and outside of the pump barrel,—a constant level liquid reservoir connected to said chamber by a passage, air 120 openings placed at the upper part of said chamber above the liquid level,—and an automatic delivery valve opening into the pump barrel below the suction valve, substantially as described and for the purpose 125 specified.

3. A pump for feeding engines with liquid fuel comprising, in combination: a cam shaft, a pump barrel or cylinder, a pump piston subjected to the action of one of the 5 cams, a return spring maintaining the contact between the piston and the cam,—an inlet or suction valve located in line with the piston axis and forming the bottom or end of the pump body or barrel,—a return 10 spring of a sufficient strength for maintaining said valve on its seat during the delivery of the pump, a sliding rod operated by the second cam of the cam shaft, an arm rigidly secured to said rod for controlling the inlet 15 side to outside opening of the suction valve, a return spring for returning the sliding rod and arm,—a liquid chamber around the suction valve and outside of the pump barrel and an automatic delivery valve opening into the pump barrel below the suction valve, substantially as described and for the 20 purpose specified.
4. A pump for feeding engines with liquid fuel comprising in combination a cam shaft, a pump barrel or cylinder, a pump piston subjected to the action of one of the 25 cams, a return spring maintaining the contact between the piston and the cam,—an inlet or suction valve located in line with the piston axis and forming the bottom or 30 the piston axis and forming the bottom or
- end of the pump barrel,— and an automatic delivery valve placed into the suction valve, which is hollow for this purpose, so that the delivery valve opens into the pump barrel directly below the suction valve, substantially as described and for the purpose 35 specified.
5. A pump for feeding engines with liquid fuel comprising, in combination: a cam shaft, a pump barrel or cylinder, a pump piston subjected to the action of one of the cams, a return spring maintaining the contact between the piston and the cam,—an inlet or suction valve located in line with the piston axis and forming the 40 bottom or end of the pump body or barrel,— and an automatic delivery valve placed in the suction valve, which is hollow for this purpose, so that the delivery valve opens into the pump barrel directly below the suction 45 valve,—and a joint, between the delivery piping and the hollow rod of the suction valve, enabling the end of said rod to reciprocate in a stuffing box during the opening and closing movements of said suction 50 valve, substantially as described and for the purpose specified.

In testimony whereof I have signed my name to this specification.

EUGÈNE HENRI TARTRAIS.
